UNITED STATES PATENT OFFICE.

HAROLD E. NOCK, OF NEWBURYPORT, MASSACHUSETTS. ASSIGNOR TO TOWLE MANUFACTURING COMPANY, OF NEWBURYPORT, MASSACHUSETTS, A CORPORATION OF MASSACHUSETTS.

DESIGN FOR A SPOON OR ANALOGOUS ARTICLE.

Application filed July 5, 1923. Serial No. 6,686. Term of patent 14 years.

To all whom it may concern:

Be it known that I, HAROLD E. Nock, a citizen of the United States, residing at Newburyport, in the county of Essex and State of Massachusetts, have invented a new, original, and ornamental Design for a Spoon or Analogous Article, of which the following is a specification, reference being had to the accompanying drawing, forming a part thereof.

In the accompanying drawing Figure 1 is a view of one face of a spoon showing my new design, Fig. 2 is a view showing the de-

sign in section at the line 2—2 of Fig. 1; Fig. 3 is a view similar to Fig. 2 at the line 3—3 of Fig. 1; Fig. 4 is a similar view to Fig. 2 at the line 4—4 of Fig. 1.

It will be understood from the delineation of the drawing that my invention comprises the ornamental features illustrated which may be applied, without change, to either face of the spoon.

I claim:

The ornamental design for a spoon or analogous article, substantially as shown.

HAROLD E. NOCK.
